UNITED STATES PATENT OFFICE.

JOSEPH C. SOEMER, OF NEWARK, NEW JERSEY.

MECHANICAL MOVEMENT.

1,331,035.

Specification of Letters Patent. Patented Feb. 17, 1920.

Original application filed April 1, 1918, Serial No. 226,073. Divided and this application filed April 10, 1919.
Serial No. 289,051.

To all whom it may concern:

Be it known that I, JOSEPH C. SOEMER, a citizen of the United States of America, residing at Newark, in the county of Essex and State of New Jersey, have invented certain new and useful Improvements in Mechanical Movements, of which the following is a specification.

This invention relates to mechanical movements especially adapted to be used for transmitting reciprocatory movements from the pistons of a series of internal combustion engine cylinders to a shaft which is disposed parallel with the cylinders, and it 10 consists in the novel features hereinafter described and claimed.

The subject-matter of the present invention is divided from my application for patent for internal combustion engines, filed 20 April 1, 1918, Serial No. 226,073.

An object of the invention is to provide a movement of the character stated which is of simple and durable structure and which will economically and positively 25 transmit movement from the pistons to the shaft, as stated, the parts being so arranged and assembled that they occupy minimum space and may attain maximum efficiency in operation.

30 In the accompanying drawings:—

Figure 1 is a vertical sectional view of the mechanical movement and portions of the engine.

35 Fig. 2 is a horizontal sectional view of the same cut on the line 2—2 of Fig. 1.

As illustrated in Fig. 1 of the drawing, the engine is shown at 1, and the said engine includes a plurality of cylinders 2 of conventional pattern. Any number of cylinders may be employed. However, it is discovered that five cylinders coöperate to advantage. Each cylinder is provided with a piston 3, which is adapted to reciprocate in a usual manner when the engine is in operation. A piston rod 4 is connected with the piston 3 by means of a ball and socket connection 5, whereby the said piston rod may have universal swinging movement with relation to the piston.

45 50 The engine shaft 6 is disposed centrally of the cylinders 2, and parallel with the same. A gear wheel 7 is fixed to the shaft 6, and meshes with a gear wheel 8, which is mounted upon a shaft 9, journaled in a casing 10, and disposed at right angles to the

shaft 6. Suitable bearings and supports are provided for the shafts 6 and 9.

A cup-shaped member 11 is fixed to the gear wheel 7, and the shaft 6 is disposed centrally of the said member. Beveled rollers 12 and 13 are journaled at the opposite sides of the member 11, and are disposed interiorly thereof. The rollers 12 and 13 are diametrically opposite each other, and their axes are in alinement. A globular member 14 is fixed to the intermediate portion of the shaft 6, and is located within the cup-shaped member 11. The engine 1 is mounted upon the top of the casing 10. A wobble disk 15 is loosely mounted on the globular member 14, and may move freely upon the same. An annular ring 16 is fixed to the base of the engine 1, and is located within the upper portion of the casing 10. The ring 16 is provided at its lower side with 75 an annular set of teeth 17. The disk 15 is provided at its edge and at its upper surface with an annular set of teeth 18, which are adapted to mesh with the teeth 17. The disk 14 is so disposed in the cup-shaped member 11 that its undersurface bears against the top of the roller 12, and its upper surface bears against the lower edge of the roller 13, as best illustrated in Fig. 1 of the drawing. The disk 15 is provided with 80 a series of bearings 19, which receive ball ends 20 provided upon the rods 4.

At the point above the roller 12, the teeth 18 of the disk 15 mesh with the teeth 17, of the ring 16. At all other points the teeth 90 18 are spaced from the teeth 17.

Consequently it will be seen that as the rods 4 are successively depressed in consequence of the downward movement of the pistons 3 to which they are attached, which 95 downward movement occurs just after the rod has passed the roller 12, and inasmuch as the disk 15 bears against the top side of the roller 12, the cup-shaped member 11 is rotated in the casing 10. In view of the 100 fact that the member 11 is fixed to the shaft 6, through the gear wheel 7, the rotary movement of the said member 11 rotates the shaft 6. From the shaft 6 rotary movement is transmitted to the shaft 9 by the 105 intermeshing gear wheels 7 and 8.

From the foregoing description, taken in conjunction with the accompanying drawings, it will be seen that a mechanical movement of simple and durable structure is pro- 110

vided, and that the same may be employed to advantage in conjunction with internal combustion engines for transmitting movement from a series of reciprocating pistons 5 to a rotating shaft disposed parallel with the cylinders of the engine and in close proximity thereto.

Having described the invention, what is claimed is:—

- 10 1. Mechanism for transmitting movement from a reciprocating piston to a shaft disposed parallel with the path of movement of the piston comprising a member fixed to the shaft, rollers journaled upon the member 15 and located diametrically opposite each other, a wabble disk movably mounted on the shaft and disposed over one roller and under the other, and means for engaging that portion of the wabble disk which is disposed over the roller.
- 20 2. Mechanism for transmitting movement from a reciprocating piston to a rotating shaft comprising a member fixed to the shaft, rollers located within the member at opposite sides thereof, a wabble disk loosely mounted on the shaft and disposed under one roller and over the other, and means for engaging that portion of the wabble disk which is disposed over the roller.
- 25 3. Mechanism for transmitting movement from a reciprocating piston to a shaft which is disposed parallel to the path of movement of the piston comprising a member fixed to the shaft, rollers journaled upon the member 30 at opposite sides and having their axes in alinement, a wabble disk loosely mounted on the shaft and having a portion extending under one roller and a portion extending over the other roller, and means adapted to 35 engage that portion of the wabble disk which extends over the roller.
- 40 4. Mechanism for transmitting movement from a reciprocating piston to a rotating shaft comprising a cup-shaped member fixed

to the shaft, rollers journaled in the cup-shaped member at the opposite sides thereof, a wabble disk loosely mounted on the shaft and having a portion disposed under one roller and a portion disposed over the other roller, and means for engaging that portion 50 of the disk which is disposed over the roller.

5. Mechanism for transmitting movement from a reciprocating disk to a shaft comprising a cup-shaped member fixed to the shaft, rollers journaled in the member, a wabble disk loosely mounted on the shaft and having a portion extending under one roller and a portion extending over the other roller, teeth carried by the wabble disk, teeth located in fixed position above the 60 wabble disk and adapted to be engaged by the teeth of the disk, and means connecting the disk with the piston.

6. A mechanism for converting reciprocating motion into rotary motion comprising 65 a shaft, a member mounted on the shaft and adapted to rotate, a disk adapted to receive a wabbling motion, means carried by the member disposed diametrically to each other and adapted to engage the opposite surfaces 70 of the disk, teeth around the edge of one face of the disk, stationary teeth mounted above the disk and adapted to engage a portion of the teeth on the disk, and means operable in parallelism with the shaft to impart movement to the disk.

7. A mechanism for converting reciprocatory motion into rotary motion, comprising 80 a member mounted to rotate, a wabbling disk, means for operating the disk, and rotatable means between the wabbling disk and member, said means being mounted on the member and engaging the wabbling disk outwardly beyond the disk operating means, and on opposite sides of the disk at diametrically opposite points thereof.

In testimony whereof I affix my signature.
JOSEPH C. SOEMER.
